US00D799904S

(12) **United States Design Patent** (10) **Patent No.:** **US D799,904 S**
(45) **Date of Patent:** **** Oct. 17, 2017**

(54) **POPCORN BOX HOLDER**

- (71) Applicants: **Jesus F. Suarez**, Uvalde, TX (US);
Diane H. Luna, Uvalde, TX (US)
- (72) Inventors: **Jesus F. Suarez**, Uvalde, TX (US);
Diane H. Luna, Uvalde, TX (US)
- (**) Term: **15 Years**
- (21) Appl. No.: **29/505,338**
- (22) Filed: **Oct. 19, 2015**
- (51) LOC (10) Cl. **07-07**
- (52) U.S. Cl. **D7/602**

(57) **CLAIM**

The ornamental design for a popcorn box holder, as shown and described.

DESCRIPTION

FIG. 1 is a perspective view of a popcorn box holder showing our new design;

FIG. 2 is another perspective view thereof;

FIG. 3 is a bottom plan view thereof;

FIG. 4 is a top plan view thereof;

FIG. 5 is a rear elevational view thereof;

FIG. 6 is a front elevational view thereof;

FIG. 7 is a right side elevational view thereof; and,

FIG. 8 is a left side elevational view thereof.

The broken lines showing a box in FIG. 1 depicts environmental subject matter and forms no part of the claimed design.

1 Claim, 6 Drawing Sheets
